UNITED STATES PATENT OFFICE.

CHARLES J. SHUTTLEWORTH, OF SPRINGVILLE, AND ORVILLE M. MORSE,
OF SILVER CREEK, NEW YORK.

APPARATUS FOR BOLTING FLOUR, &c.

SPECIFICATION forming part of Letters Patent No. 225,536, dated March 16, 1880.

Application filed May 13, 1879.

To all whom it may concern:

Be it known that we, CHARLES J. SHUTTLEWORTH, of Springville, in the county of Erie and State of New York, and ORVILLE M. MORSE, of Silver Creek, in the county of Chautauqua and State of New York, have invented new and useful Improvements in Apparatus for Bolting Flour and other Material, of which the following is a specification, reference being had to the accompanying drawings.

This invention relates to a bolting apparatus in which an inclined screen or sieve is employed instead of the rotating reels which are now generally used. These reels are ordinarily composed of a six-sided frame covered with bolting-cloth, and the meal bolted therein rests upon the lower section of bolting-cloth, and is gradually lifted up as the reel rotates, and held by the rib of the reel-frame until the angle of the section supporting the meal becomes so steep that the rib is unable to retain the meal any longer, when the whole mass of meal slides off and drops down upon the lowest section of the reel. This operation is repeated six times during each revolution of a six-sided reel, and the bolting is effected by only one section of the reel at a time, and only during the short time in which the meal is in motion, as very little flour passes through the meshes when the meal is at rest.

The object of our invention is to construct a bolting apparatus in which the process of bolting can be carried on more expeditiously, more conveniently, and at less expense than in ordinary bolting-reels; and our invention consists, principally, of a bolting apparatus containing an inclined bolting-surface and an elevating mechanism so arranged that the meal is delivered by the elevating mechanism directly at or above the upper end of the inclined bolting-surface, and caused to pass repeatedly over the bolting-surface, whereby the meal is rapidly bolted; also, of various details of construction, as will be hereinafter fully set forth.

In the accompanying drawings, Figure 1 is an elevation of our improved apparatus with a portion of the outer case removed. Fig. 2 is a cross-section thereof. Fig. 3 is a top-plan view with the top of the case removed. Fig. 4 is an end view of the machine.

Like letters of reference designate like parts in the several figures.

A represents the case of the machine, supported on legs or posts B. C is the inclined bolt or screen, and D the elevating-wheel.

The inclined bolt or screen C consists of one or more frames covered with bolting-cloth, and is arranged in inclined guides or ways ee 60 in one side of the case A, so that the screen C can be readily removed from the machine when required.

As shown in the drawings, the elevating-wheel is composed of a suitable number of 65 long buckets or wings, f, connected with the shaft g of the wheel by spiders h.

i represents the concave bottom of the case A, which is so formed that the wings or buckets f of the elevating-wheel run in close contact with the concave bottom and pick up the meal as it falls on the same.

The inclined screen C is arranged to face the lower portion of the elevating-wheel, so that the meal, as it escapes from the buckets 75 f, is delivered against the side portion of the case A at or above the upper edge of the inclined screen C.

J represents a conveyer of any suitable and well-known construction, which is arranged 80 underneath the inclined screen C, and collects the flour and middlings which pass through the meshes of the screen and conducts the same to the proper discharge-openings j j' j'', respectively.

k k are knockers or hammers which jar the screen C by striking against the upper bar of the frame. The knockers k are secured to a rock-shaft, l, which is supported in bearings l', and operated by a cam or projection, m, on the outer end of the conveyer-shaft. The latter is driven by a crossed belt, n, from a pulley,

N, mounted on the shaft g of the elevating-wheel, or by any other suitable device.

The frame of the screen C is preferably provided on its bottom edge with a strip, n', of 5 rubber or other elastic material to facilitate the jarring of the screen.

The side of the case A opposite the under side of the screen C is made open and provided with a removable panel or door, P, so 10 that by opening the latter the attendant can examine the under side of the screen and apply a brush to remove any material that may adhere thereto.

The elevating-wheel D and screen C are arranged in a slightly-inclined position, in the manner of an ordinary flour-bolt, to impart to the material a motion toward the tail end of the machine.

q is the feed-spout, entering the top of the 20 case A at the head of the machine, and r is the bran-discharge spout, arranged at the tail end of the concave bottom i of the case.

The ground meal or other material to be separated is fed into the machine through the 25 spout q, and falls either upon the buckets f of the elevating-wheel or upon the bottom i of the case, where it is scooped up by the buckets and elevated. As the wheel D revolves, the material elevated by the buckets f is discharged 30 against the upper end of the screen C at the head of the machine, and is caused to roll over the inclined surface of the screen back to the concave bottom of the case. Owing to the inclined position of the wheel D and 35 screen C, the material travels at the same time toward the tail end of the machine.

The screen C is provided with bolting-cloth of different degrees of fineness in any approved and well-known order.

40 Assuming that the finest cloth is placed at the head of the screen, the superfine flour will pass through the cloth at the head of the screen and the inferior grades of flour will pass through the cloth nearer the tail end of the screen. The last portion, s, of the screen will 45 be sufficiently coarse to permit the passage of the middlings, and the bran will be discharged through the opening r.

The conveyer-trough t will be provided with 50 a suitable number of cut-offs, so that any desired portion of the flour bolted through may be returned to the case for re-bolting.

If desired, the different grades of bolting-cloth may each be mounted on a separate 55 frame, so that each may be removed independent of the others and be replaced by any other desired grade, thereby enabling the miller to adapt the bolting-surface to the particular work required to be performed.

60 Upon removing the screen C from the case A both sides of the screen can be thoroughly cleaned, while in a reel only the outside of the cloth can be reached. The space underneath

the screen C into which the flour is bolted is entirely separated by the bolting-surface from 65 the space containing the meal, thereby preventing the floating specks which occur in every bolting operation from coming in contact with the flour, as they do when ordinary reels are used, and doing away with the speck-boxes used in ordinary reels for collecting 70 these floating specks.

The bolting-screen C is preferably made of the same size as one of the sections of an ordinary bolting-reel, and the elevating-wheel 75 somewhat larger, so as to deliver the meal at the top of the screen.

In our improved bolting apparatus the meal to be bolted is divided into a large number of small parts, according to the number of wings 80 or buckets employed, and the meal is in consequence brought in contact with the bolting-surface in an almost continuous thin stream, whereby the bolting-surface is kept almost continually in operation, and the operation of 85 bolting performed very rapidly.

The granules of flour strike the meshes of the stationary bolting-surface always in the same direction, so that granules of the same size only will pass through any given portion 90 of the bolting-surface, while in rotating reels the granules of flour strike the bolting-surface at various angles, according to the position which the section of the reel may occupy at the moment that the granule of flour strikes 95 the same; hence the flour bolted by our improved machine is more uniform than that bolted through rotating reels, and consequently works better in baking.

In our improved machine the same amount 100 of work performed by a rotating reel is accomplished with a small portion of the bolting-cloth required in a reel, and our improved machine is consequently produced at considerably less expense.

105 The elevating mechanism operates at the same time to cool the meal and prevent the bolting-surface from becoming clogged. The buckets or wings f of the elevating mechanism may be secured to the periphery of a tight drum or cylinder which is closed at its head, or they may be attached to endless belts or chains running over suitable pulleys, as may be preferred.

We claim as our invention—

115 1. In a bolting apparatus, the combination, with an elevating mechanism constructed substantially as described, of an inclined screen facing the elevating mechanism and composed of sections having different degrees of fineness 120 arranged side by side, whereby the material fed into the machine is separated into fine and coarse portions from the head toward the tail of the machine, substantially as set forth.

2. In a bolting apparatus, the combination, 125 with an elevating mechanism provided with
